AIR TRANSLATING APPARATUS

Gustav H. Koch and Charles O. Egerton, Springfield, Mass., assignors to Westinghouse Electric Corporation, East Pittsburgh, Pa., a corporation of Pennsylvania

Application February 14, 1945, Serial No. 577,816

9 Claims. (Cl. 230—275)

1

Our invention relates to air translating apparatus and, more particularly, to an electric fan of the type which includes a propeller and a guard disposed around and enclosing said propeller.

One object of the invention is to produce an improved fan of the type set forth.

The guard of an electric fan is usually made of relatively heavy gauge wire and is composed of intersecting segments suitably secured together at predetermined points, the guard as a whole being secured to the casing of the fan motor by screws or other, separable, fastening device.

It is, therefore, a further object of our invention to produce an improved structure whereby the guard is secured to the fan motor casing without the use of special fastening means and whereby the connection of the guard with the fan casing is completely concealed.

A still further object of the invention is to produce the improved structure described in an inexpensive manner.

These and other objects are effected by our invention as will be apparent from the following description and claims taken in connection with the accompanying drawings, forming a part of this application, in which:

Fig. 1 is a side elevational view of an electric fan embodying our invention;

Fig. 2 is an enlarged, fragmentary, composite, perspective view showing details of construction;

Fig. 3 is an enlarged view partly in section and partly in rear elevation, showing details of construction; and

Fig. 4 is a view, similar to Fig. 2, showing a slightly modified form of construction.

In the accompanying drawings, there is shown an electric fan including a supporting pedestal 10, a motor casing 12, and a propeller 14 adapted to be driven by a shaft 16 of an electric motor 18 enclosed within the motor casing. The fan motor casing is pivoted to the pedestal 10 at 17 and is locked in adjusted position by a wing nut 18. A guard 20 protects the propeller 14. If desired, the fan may be provided with a conventional oscillating mechanism 22.

In the preferred embodiment of our invention, we make the fan motor casing in two horizontally divided sections, and we provide the guard with horizontally extending arms adapted to be clamped between the upper and lower motor casing sections. Also, we provide one of the casing sections with vertically disposed apertures and we provide the guard with upwardly extending arms adapted to engage said apertures.

2

As shown in Figs. 1 to 3, the motor casing is formed of an upper section 24 and a lower section 26 having juxtaposed flat surfaces 28 and 30, respectively, which abut along a horizontal plane when the casing sections are assembled, as shown in Fig. 1. The upper and lower sections are clamped together by any suitable means such as screws or the like 32.

The opposite side walls of the lower section are provided with inwardly projecting lugs 34, the upper faces of which are flush with the horizontal surface 30 of the lower casing section. The upper surfaces of the lugs 34 are provided with horizontally disposed elongated recesses 36. The front portion of the lower casing section is provided with a pair of spaced, vertically disposed openings 38. As will be seen from Fig. 3, the recesses 36 and the openings 38 are disposed symmetrically at either side of the motor casing. Preferably, the recesses 36 extend longitudinally, or rearwardly from front to rear of the lower casing section.

The opposite side walls of the upper motor casing section are provided with inwardly projecting lugs 40, the lower faces of which are preferably flush with the lower surface 28 of the upper motor casing section. The lugs 40 are adapted, when the motor casing sections are assembled, to overlie the recesses 36. Also the front portion of the upper motor casing section 24 is provided with a pair of spaced, exterior recesses 42.

The fan guard 20 may be constructed in any desired manner and may be of any desired shape. In order to carry out our invention, the guard is provided with horizontally disposed arms, adapted to engage the recesses 36, and with vertically disposed, arms adapted to engage the openings 38. As illustrated, the guard is provided with rear downwardly extending limbs 44 which terminate in rearwardly extending horizontal arms 46 adapted to seat in recesses 36 and with upwardly extending rear arms 48 adapted to engage the vertical openings 38. The entire guard, or at least the limbs 44 and 48 thereof are preferably formed of wire having a certain amount of resiliency.

Assembly—Figs. 1 to 3

With the upper casing section removed the guard 20 is positioned so as to enclose the propeller 14, and the upper ends of the vertical arms 48 are inserted partly upwardly into the vertical openings 38. The horizontal arms 46 of the guard are then sprung apart until they clear the sides

of the lower casing section. The guard is then moved upwardly until the arms 46 clear the upper surface 30 of the lower casing section and are seated in the recesses 36. The vertical arms 48 now reach their uppermost position in the openings 38. As will be seen from Fig. 2, the side, front and rear end walls of the recesses 36 prevent lateral and axial movement of the arms 46 of the guard. With the arms 46 seated in the recesses 36, the upper casing section is placed on and clamped to the lower motor casing section, as shown in Figs. 1 and 3. In this position the rear vertical limbs 44 of the guard are seated in the recesses 42 in the front portion of the upper motor casing section.

Since the upper surfaces of the arms 42 are flush with the upper surface 30 of the lower motor casing, the arms 42 will be tightly clamped in position by the lugs 40 of the upper lower casing section, and since the vertical arms 48 can only be withdrawn from the openings 48 by downward movement of the entire guard, it will be seen that the guard as a whole is securely fastened in position.

In Fig. 4 there is shown a slightly modified construction which differs from the structure of Figs. 1 to 3 only in the manner in which the horizontal limbs of the guard are clamped between the upper and lower motor casing sections. In this construction, the opposite side walls of the lower casing section 26 are provided with spaced inwardly projecting ribs 50, the upper surfaces of which are flush with the upper surfaces 30 of the lower casing section. The upper surfaces of the ribs 50 are provided with recesses 52 for seating the spaced portions of the horizontal arms 46 of the guard. The upper casing section 24 is provided with an inwardly extending rib 54 which, when the motor casing sections are assembled, will engage the arms 46 of the guard. The upper motor casing section 24 is provided with front recesses 56 for accommodating the downwardly extending rear limbs 44 of the guard.

As shown in Fig. 4, the upper surface of the limbs 46 are flush with the upper surfaces of the ribs 50 and the upper surfaces of the lower motor casing so that they are frictionally engaged by the ribs 54. If desired, the portions of the arms 46 suspended between the ribs 50 may be initially bent upwardly slightly, or may be otherwise made to project slightly above the upper surfaces of the ribs 50 so that, when the motor casing sections are assembled, the ribs 54 will slightly deform the arms 46, thus more firmly clamping them in position.

The assembly of the structure shown in Fig. 4 is carried out in the same manner as that described in connection with Figs. 1 to 3.

While in the drawings we show the horizontal recesses and the vertical openings as being formed in the lower casing section, it is obvious that the recesses and openings referred to, or either of them, may be provided in the lower or in the upper motor casing section, without departing from the scope of the invention.

It will also be seen that the fan guard is secured in position without the use of screws or other extraneous separable fastening means and that the guard is secured in position by entirely concealed means.

While we have shown our invention in several forms, it will be obvious to those skilled in the art that it is not so limited, but is susceptible of various other changes and modifications without departing from the spirit thereof.

What we claim is:

1. In an electric fan including a propeller and a motor for driving said propeller, a motor casing formed of at least two separable sections, means for fastening said sections together, a guard for said propeller, an arm carried by said guard and clamped between said motor casing sections, and means for bracing said guard for preventing relative displacement thereof about said arm.
2. The structure recited in claim 1 in which said motor casing is formed of horizontally-divided upper and lower sections and in which said arm extends horizontally and is clamped between the abutting surfaces of said sections.
3. The structure recited in claim 1 in which said motor casing is formed of horizontally-divided upper and lower sections, there being a horizontally-disposed recess formed in the abutting surface of one of said sections, said arms being seated in said recess and clamped between said sections.
4. In an electric fan including a propeller and a motor for driving said propeller, a motor casing formed of at least two separable sections, means for fastening said sections together, a guard for said propeller, and an arm carried by said guard and extending in the plane of separation of said motor casing sections, one of said sections being provided with an opening at an angle to the plane of separation of said sections, together with a second arm carried by said guard and disposed in alignment with and adapted to be inserted into said opening.
5. In an electric fan including a propeller, and a motor for driving said propeller, a motor casing formed of upper and lower horizontally-divided sections, means for fastening said sections together, a guard for said propeller, said guard including a pair of spaced arms extending rearwardly and horizontally therefrom and clamped between said sections, there being a pair of recesses formed in the horizontal surface of one of said sections leading rearwardly from a point near the front end of said one casing section for accommodating said arms, and means cooperating with said arms to hold said guard against displacement when said casing sections are assembled.
6. In an electric fan having a propeller and a motor for driving said propeller, a motor casing formed of horizontally-divided upper and lower sections, means for fastening said sections together, a guard for said propeller, there being horizontally-extending recesses in the horizontal abutting surface of one of said sections leading rearwardly from near the end of said one section adjacent said guard, and vertically-extending openings in a portion of one of said sections adjacent said guard, horizontally-disposed arms carried by said guard and clamped between said sections, said arms being seated in said recesses, and vertically-disposed arms also carried by said guard and engaging said openings.
7. In an electric fan including a propeller, a motor for driving said propeller, a motor casing formed of upper and lower horizontally divided sections, means for fastening said sections together, a guard for said propeller, said guard including a pair of upwardly-extending arms and another pair of spaced arms extending rearwardly and horizontally from said guard, one of said sections having formed therein a pair of spaced vertically-disposed openings for receiving said upwardly-extending arms, there being a pair of recesses formed in the horizontal surface of

one of said sections leading rearwardly from a point near the front end thereof for accommodating said other pair of spaced arms when clamped between said sections.

8. In an electric fan, a motor casing having a substantially horizontal axis and comprising lower and upper sections having complementary abutting surfaces, means for fastening said sections together, said lower section having a pair of opposite substantially axially-disposed recesses formed in the abutting surface thereof and also having a pair of upwardly-extending openings substantially normal to said recesses, and a fan guard carrying a pair of substantially vertical arms engageable in said openings, and a pair of substantially axial arms adapted to seat in said recesses, respectively, said upper section being adapted for locking engagement with said axial arms when mounted on said lower section. 10

9. In an electric fan, a motor casing having complementary sections with abutting surfaces, means for fastening said sections together, the first of said sections having longitudinally-disposed recesses formed in its abutting surface and leading inwardly from a point near one end thereof, and having openings extending through said portion at an angle with respect to said re-

cesses, and a fan guard adapted to be supported by said casing, said guard having longitudinally-disposed arms adapted to seat in said recesses in clamping relation between said sections and angularly-extending arms adapted to be engaged in said openings when said casing and guard are assembled.
